CHARLES H. ROLLASON, OF WHEELING, WEST VIRGINIA, ASSIGNOR TO WHEELING STEEL CORPORATION, OF WHEELING, WEST VIRGINIA, A CORPORATION OF DELAWARE

SEALING RING FOR CANS AND PAILS

Application filed October 15, 1930. Serial No. 488,931.

This invention relates to a sealing ring for cans and pails, and it has for its primary object to provide a simple and improved form of ring whereby covers may be securely attached to the bodies of cans and pails.

A further object is to provide a head attaching device, or sealing ring, of that type embodying a skirt portion which is adapted to be turned into underlying seated relation to the rim-roll or bead, wherein the skirt portion is preliminarily and initially deformed to provide lines defining angularly related areas along which lines may occur the buckling that results from inward drawing of said skirt to bead-engaging position.

In describing said invention in detail, reference is herein had to the accompanying drawings, in which—

Figure 1 is a view, partly in section and partly in side elevation, showing my invention;

Figure 2 is a detail section of a pail body with a cover mounted thereon and showing the sealing ring applied thereto preliminary to sealing said cover in place; and—

Figure 3 is a similar view showing the ring in sealing position.

Referring to said drawings, 1 designates a can or pail body having an outwardly turned terminal bead or rim roll 2 at its open end. Said rim roll constitutes a seat adapted to be conformably engaged by the arcuately curved terminal flange 3 of a removable closure or cover 4.

The cover is secured in place by means of a one-piece sheet-metal sealing ring, herein generally designated by the reference numeral 5, which comprises a body 6 having a skirt portion 7, the said body having a curvature in cross section substantially corresponding with that of the cover flange 3 to be embraced thereby. Said skirt portion 7 normally occupies a vertical position, depending from, or being a continuation or extension of, the outer portion of said body. A hem 8 composed of one or more folds of the metal is formed on the lower edge of the skirt 7 for the purpose of reinforcing or stiffening said edge.

The skirt is designed to be turned inward

ly into closely tucked underlying seated relation to the under side of the rim roll 2 for securing the cover in firmly seated relation to the can or pail body. Manifestly, in so tucking the skirt in its seated position, the diameter of the skirt is materially reduced and, therefore, provision is made for such an absorption of the excess material as will cause the hem edge 8 to snugly hug the under side of the rim roll 2. For this purpose, said skirt, or the hem edge thereof, has rolled therein throughout its circumference a series or succession of hollow indentations 9, whereby is produced a continuous line of outwardly directed angular projections 10, preferably of pyramidal form, wherein each of the base lines of each pyramid is diagonally inclined and is formed by prolongations of the base lines of adjacent pyramids, as shown.

The defining lines of said projections, or pyramids, constitute definite lines along which, as the skirt is being tucked under the rim roll, the metal of the skirt readily buckles or collapses to accommodate itself to the reduced diameter produced, the height of said pyramids being correspondingly increased with such collapse to the extent required to effect absorption of the excess material.

What is claimed is—

1. A sheet metal sealing ring of the character described, comprising a body, arcuate in cross section, and a skirt, said skirt being formed by prolonging downwardly the outer edge portion of said body, said skirt having therein definite pre-formed lines of deformation along which, upon the application thereto of inwardly directed bending force, it readily collapses to effect absorption of excess material thereof.

2. The combination with a container having a rim roll, and a cover having an annular flange for seating upon said roll, of a sheet metal sealing ring comprising a body, arcuate in cross section, for closely seating upon said flange, and a skirt depending vertically from the outer edge portion of said body, said skirt being deformed by the provision therein of a succession of close-

ly associated outwardly pressed projections having angularly related defining lines along which may occur material-absorbing collapse resulting from the application to said skirt 5 of inwardly directed contracting force.

8. The combination with a container having a rim roll, and a cover having an annular flange for seating upon said roll, of a sheet metal sealing ring comprising a body 10 shaped to seat upon said flange, and a skirt formed by prolonging downwardly the outer edge portion of said body, said skirt having formed therein a succession of pyramidal projections providing angularly related 15 areas whose defining lines constitute prescribed lines of material-absorbing collapse resulting from the application to said skirt of contracting force.

In testimony whereof, I affix my signature.
20 CHARLES H. ROLLASON.
